(57) **CLAIM**

We claim the ornamental design for a capillary array for DNA sequencer, as shown and described.

DESCRIPTION

FIG. 1 is a front, top and right side perspective view of capillary array for DNA sequencer showing our new design; FIG. 2 is a front elevational view thereof; FIG. 3 is a rear elevational view thereof; FIG. 4 is a top plan view thereof; FIG. 5 is a bottom plan view thereof; FIG. 6 is a right side elevational view thereof; and, FIG. 7 is a left side elevational view thereof. The broken lines are included for the purpose of illustrating unclaimed portions of the capillary array for DNA sequencer and form no part of the claimed design.
